US00D980586S

(12) **United States Design Patent** (10) **Patent No.:** **US D980,586 S**
(45) **Date of Patent:** **** Mar. 14, 2023**

(54) **SHIRT**

- (71) Applicant: **NIKE, Inc.**, Beaverton, OR (US)
(72) Inventors: **Charlotte Harris**, Portland, OR (US);
Erick Lopez, Beaverton, OR (US);
Brianna Vizcaino, Beaverton, OR (US)
(73) Assignee: **NIKE, Inc.**, Beaverton, OR (US)
(**) Term: **15 Years**
(21) Appl. No.: **29/819,947**
(22) Filed: **Dec. 17, 2021**
(51) LOC (14) Cl. **02-02**
(52) U.S. Cl. **D2/840**
(58) **Field of Classification Search**
USPC D2/609, 717, 731, 840, 841, 844, 853
CPC A41D 1/04; A41D 13/0015
See application file for complete search history.

(57) **CLAIM**

The ornamental design for a shirt, as shown and described.

DESCRIPTION

FIG. 1 is a front perspective view of a shirt showing our new design;

FIG. 2 is an opposite side front perspective view thereof;

FIG. 3 is a rear perspective view thereof;

FIG. 4 is an opposite side rear perspective view thereof;

FIG. 5 is a front view thereof;

FIG. 6 is a rear view thereof;

FIG. 7 is a side view thereof;

FIG. 8 is an opposite side view thereof;

FIG. 9 is a front perspective view showing an alternate embodiment of our design;

FIG. 10 is an opposite side front perspective view thereof;

FIG. 11 is a rear perspective view thereof;

FIG. 12 is an opposite side rear perspective view thereof;

FIG. 13 is a front view thereof;

FIG. 14 is a rear view thereof;

FIG. 15 is a side view thereof; and,

FIG. 16 is an opposite side view thereof.

The broken lines immediately adjacent to the bottom of the shaded areas define the bounds of the claimed design and form no part thereof. The broken lines depicting the remainder of the shirt form no part of the claimed design.

1 Claim, 16 Drawing Sheets
